B. FREILE.
TELEPHONE SWITCHBOARD APPARATUS,
APPLICATION FILED AUG. 30, 1920.

1,423,930.

Patented July 25, 1922.

Inventor:
Bruce Freile.

by *Jack C. Barnes* Atty.

UNITED STATES PATENT OFFICE.

BRUCE FREILE, OF BOGOTA, NEW JERSEY, ASSIGNOR TO WESTERN ELECTRIC COMPANY, INCORPORATED, OF NEW YORK, N. Y., A CORPORATION OF NEW YORK.

TELEPHONE SWITCHBOARD APPARATUS.

1,423,930.

Specification of Letters Patent. Patented July 25, 1922.

Application filed August 30, 1920. Serial No. 406,982.

To all whom it may concern:

Be it known that I, BRUCE FREILE, a subject of the King of Great Britain, residing at Bogota, in the county of Bergen, State 5 of New Jersey, have invented certain new and useful Improvements in Telephone Switchboard Apparatus, of which the following is a full, clear, concise, and exact description.

10 This invention relates in general to telephone switchboard apparatus. The invention provides a unit strip for an operator's checking multiple.

Checking multiples are used at toll offices 15 in automatic telephone systems and are provided to enable the toll operator to check the correctness of a subscriber's statement regarding the number of the station from which he is calling. When such systems are 20 used, it is customary to have terminals for all lines accessible to each operator. Under these conditions it is essential that they occupy as little space as possible and that the terminals be multiplied through a number 25 of sections of the board.

The method of testing in such a system is 30 similar to the busy test of a manual switchboard where the busy condition of a line is indicated by a tone in the operator's receiver 35 upon touching the tip of a plug to the jack sleeve of a busy line. The system by which this is accomplished is described in detail in application Serial No. 285,411 filed Mar. 27, 1919, and being no part of this invention 40 will not be further described herein.

The object of this invention is to provide 45 an arrangement of such test terminals which shall be inexpensive, compact, and convenient.

40 The invention in its preferred form consists of a plurality of bars of conductive material arranged in a number of horizontal rows and held in this position by insulating material, preferably phenol condensation 45 product or similar substance, moulded about the bars, to form a block in form somewhat resembling a jack strip. The bars are exposed on the face of the block and extend through the rear for connection with the 50 circuit wiring. Grooves cut on the face of the block and across the face of the bars serve as a guide for an operator's plug tip and also as a means for retaining coloring

matter to indicate to the operator traffic conditions obtaining on certain lines, such 55 as for example "service denied," "limited service," "official lines" and the like.

A clearer understanding of the invention may be had by reference to the drawings which show its preferred form. Fig. 1 60 shows a front view with an operator's plug in testing position on a line testing terminal. Fig. 2 shows a cross sectional view taken along the plane indicated in Fig. 1 by the line 2-2. In Fig. 2, portions of one of the 65 terminal bars are cut away to show details of its interior form.

A suitable number of terminal rods 1 are arranged so as to form both horizontal and vertical rows. About the terminal rods 1 70 is moulded a mass of insulating material, preferably hard rubber, phenol condensation product or the like, to form a rectangular block 2, having the shoulders 3 to serve as a means to support the block 2 between 75 the vertical stiles of a switchboard frame. A block is thus formed which is adapted to be mounted in a switchboard in the same manner as a strip of jacks in a manual system. Each of the terminal rods 1 is provided with a ring cut 11 which cooperates with the moulded material of the block 2 to prevent any possible slipping out of position in the block. A hole 10 is drilled along the axis of the terminal rods 1 to assist in 80 85 centering and setting them up preparatory to moulding the block 2.

At the front of the block 2, the terminal rods 1 are exposed so that an electrical contact may be made with the tip of an operator's plug 4 with any one of such terminals. For the purpose of making it more convenient to find any particular one of the terminals 1 with the plug 4, grooves 5 are cut in the face of the block 2, crossing the face of 90 95 the terminals 1. In this way the operator, after locating the horizontal row in which the line terminal is located, may guide the testing plug 4 along the proper one of the horizontal grooves 5 until she has located 100 105 the desired terminal.

The grooves cut in the faces of the conductive bars 1 are slightly narrower than the grooves 5 in the block 2. In this way the plug tip in passing a contact face is 105 certain to make contact.

The terminals 1 protrude beyond the rear of the block 2 terminating in flat portions 6 in which a hole 7 is drilled or punched to accommodate suitable electrical wire connections.

As shown in the drawing, there are one hundred terminals grouped in the block 2, there being five rows of twenty terminals. This provides a compact arrangement, convenient not only to install, but also to operate. However, should a greater number of such terminals be desired in a single strip or block, they may be so rearranged without departing from the invention.

15 An additional groove 8 is provided at the top of the block 2 which is adapted to be filled with paint or other coloring matter for the purpose of marking out the terminals into groups of hundreds so as to further 20 assist an operator to find the proper terminal. For a similar purpose are provided the marking means 9 which consists of a series of small holes bored in the face of the block 2 and filled with bright colored pigment. These are placed at intervals of five 25 terminals.

The grooves 5, in addition to their use as guides, are also adapted to hold coloring matter showing the character of the line to 30 which they are adjacent, such as "party line," "denied service," "coin box," "private branch exchange," and the like.

What I claim is:

1. A test block comprising a plurality of parallel rows of conductive bars placed side by side, each conductive bar terminating at one end in a grooved contact face, and at the other end terminating in a lug adapted to receive conductor wiring; and a block of insulating material in which said bars are insulatingly imbedded, said block being provided with a groove for each row of conductive bars, said groove registering with the grooves in the contact faces of the said conductive bars in each such row. 45

2. A test block comprising a plurality of parallel rows of conductive bars placed side by side, each conductive bar terminating at one end in a grooved contact face and at the other end terminating in a lug adapted to receive conductor wiring; and a block of insulating material in which said bars are insulatingly imbedded, said block being provided with a groove for each row of conductive bars, said groove being wider than 50 the groove in the contact faces of the conductive bars and narrower than the contact face of the conductive bars and registering with the grooves in the contact faces of said conductive bars in each such row. 60

In witness whereof, I hereunto subscribe my name this 23rd day of August, A. D. 1920.

BRUCE FREILE.
